UNITED STATES PATENT OFFICE.

EMIL TAUSSIG, OF NEW YORK, N. Y.

DESIGN FOR A TANK FOR DISINFECTING FLUIDS.

SPECIFICATION forming part of Design No. 30,745, dated May 9, 1899.

Application filed April 13, 1899. Serial No. 712,931. Term of patent 7 years.

To all whom it may concern:

Be it known that I, EMIL TAUSSIG, a citizen of the United States, and a resident of New York, in the county and State of New York, have invented a new and original Design for Tanks for Disinfecting Fluids, of which the following is a specification, reference being had to the accompanying drawings, forming a part thereof.

The leading feature of my design consists in a tank for disinfecting fluid of a general oblong form having an elongated portion extending transversely of and uprising from its upper surface.

In the accompanying drawings, Figure 1 is a top plan view of the tank. Fig. 2 is a view in side elevation, and Fig. 3 is a view in end elevation.

A represents the body of the tank as a whole, ²⁰
a its top, a' its side, and a² its end.

B represents the elongated portion uprising from the top.

What I claim is—

The design for a tank for disinfecting fluid, substantially as shown and described. ²⁵

In testimony that I claim the foregoing as my invention I have signed my name, in presence of two witnesses, this 25th day of January, 1899.

EMIL TAUSSIG.
